DISPLAY BOX CONSTRUCTION

Max Simon, New York, N. Y., assignor to I. B.
Kleinert Rubber Company, New York, N. Y.

Application September 8, 1932, Serial No. 632,142

13 Claims. (Cl. 206—44)

This invention relates to display box construction.

In the construction of boxes used for shipping articles to a point of distribution, in which the box itself forms a means for placing the articles on display at the point of distribution, and for advertising the articles when so displayed, to assure that such boxes will be given a conspicuous place for display and, once so positioned, will be so retained until all the articles contained in the box have been disposed of, is a problem which has tried the ingenuity of box manufacturers. One well-known type of such containers has a cover, hingedly associated therewith. In the use of such boxes, the cover, by slight contact of an attendant therewith, or even from a breeze, will gravitate to closed position, making itself somewhat a nuisance to the attendant. The seemingly small matter of the psychology of this situation is, in fact, a serious matter in the merchandising of such articles as are to be displayed in this manner. Attendants have been known to be so provoked as to put those goods aside, and place others on display in their stead. The presentation to the buying public of the advertising argument found on the covers or cards, within the box, have all been studied for that purpose.

Now, in this invention, there is created an inducement to the salespeople to dispose of the goods as quickly as possible for a secondary benefit to be derived personally from the container and, at the same time, the container is highly presentable for disposing the goods on display. The particular container involved is one with a hinged cover. However, by construction of the container, an advertising-bearing placard serves to assure positive retention of the cover in open position against any of the influences above noted. By this means, such advertising matter is, at all times, assured proper display. It is, therefore, an object of the invention to provide a container of articles which, when opened and properly assembled, not only will display to best advantage the articles therein contained, but also will positively retain an advertising card in visible relationship to the articles, while the card itself will operate to prevent unwarranted closing of the box cover.

After a box of the character indicated has been used for displaying the articles therein contained, and such articles have all been sold, the container, if made practicable for further use, preferably in other associations, will lend an inducement to the salespeople to further the sales of those articles. A container, capable of application, in this manner, to a plurality of uses, is a highly desirable

unit. In the embodiment of the invention herein disclosed, the container has been made up in such manner that, after the articles ordinarily packed therein have been disposed of, it may constitute a plurality of containers, each of which may serve individually or in conjunction with the other container for many purposes. At the same time, certain of the elements, which make this subsequent functioning possible, also are coordinated in the container structure to make it more effective for display purposes.

The container comprises a pair of receptacles, nesting and cooperating in such manner that, with the production of a simple, efficient, neat structure, there still is assured the accomplishment of the results above set forth. The outer casing or receptacle into which may be nested, preferably snugly, another receptacle, has associated therewith a cover, hinged to that receptacle and, by flexible bands, limited in its movement with relation to the receptacle. The cover is intended to be sustained, in one embodiment, substantially in upright position; advertising matter on the upright cover will be displayed effectively in connection with articles housed within the inner receptacle.

The height of the inner receptacle is related to the depth of the outer receptacle in such manner that, by their association, when nested, the top edge of the inner receptacle will extend beyond the top edge of the outer receptacle. A shoulder, in association with a bead, is thus constructed; over these, the cover will seat. For association with the inner receptacle there is provided preferably a board closure. The extent of this closure is intended to be just about that of the top of the inner receptacle; when the cover seats upon the receptacle, the cavity of the cover will enclose top edges of the inner receptacle and the closure.

The upper edge of the inner receptacle is notched at a pair of points closely adjacent the hinge of the cover; into the notches is intended to be seated the board closure, which then extends within the shallow depth of the cover. Preferably, the width of the board closure, the depth of the notches, their relationship to the hinge point, and the depth of the cover are associated so that the board closure, when so used, will at least be in slight compression. In any case, when so associated, the board closure will be in position to engage with the front wall of the cover to prevent downward movement thereof unless the board closure be moved out of the associated relationship. The board is so formed that it may be reduced in its extent and then

nested within the inner receptacle and against the top edges of partitions defining compartments in that receptacle to provide a snug closure for that receptacle.

5 Other objects of this invention will herein-after be set forth, or will be apparent from the description and the drawing, in which is illustrated an embodiment of a display container carrying out the invention.

10 The invention, however, is not intended to be restricted to any particular construction or arrangement of parts, or to any particular application of such construction, or to any specific manner of use, or to any of various details thereof, 15 herein shown and described, as the same may be modified in various particulars or be applied in many varied relations without departing from the spirit and scope of the claimed invention, the practical embodiment herein illustrated and described merely showing one of various forms and modifications in which the invention might be embodied.

20 On the drawing, in which the same reference characters refer to the same parts throughout, and 25 in which is disclosed a preferred embodiment:

Fig. 1 is a perspective view of a container, embodying the invention, and shown closed;

Fig. 2 is a perspective view of the same container, shown open, and broken away in part 30 to illustrate clearly details of construction; and

Fig. 3 is a perspective view of the inner receptacle, shown removed from its association with the outer receptacle and with the board top in nested association therewith, portions being 35 broken away so that elements of construction are made clearly apparent.

In one method of constructing the box 10, shown on the drawing, two receptacles 12 and 14 may be nested snugly, one within the other. It 40 is to be understood, of course, that, within certain degrees of this invention, the two receptacles may be consolidated into, or made as, a single, unitary container. The receptacles may be made of any suitable material, such as paper board, 45 wood, or metal. The walls of the outer receptacle are of suitable thickness, the rear wall 16 having hinged, at its top rear edge 18, a cover 20, which may be of similar material. The cover itself 50 may be a shallow, inverted container, in extent substantially the same as receptacle 12. Therefore, when positioned in closed relationship, it will, as shown in Fig. 1, form with receptacle 12, a smooth, exterior surface. Suitable flexible members, such as the bands 22, may be extended 55 between the inner walls of the cover and the inner faces 24 of side walls 26 of receptacle 12 to limit opening movement of the cover with respect to the receptacle.

Receptacle 14 is here shown to have walls, the 60 height of which are such that, when seated within receptacle 12, these walls will extend above the top edges of the walls of receptacle 12, thereby defining a bead 28, and with the top edge of receptacle 12, forming a shoulder 30. Therefore, when 65 the cover is moved to closed position, it not only will seat upon the top edge of receptacle 12, but also will be retained in that position by bead 28.

In bead 28 are also formed slots 32, preferably inclined slightly rearwardly. These slots are 70 designed for the reception of an end edge of a member 34. This member may be made of material similar to that used for the construction of the receptacles and the cover; one material having the properties desired for this element is cardboard. The member has an extent such that it 75

will cover completely the top edges of the walls of receptacle 14, if used for that purpose. Therefore, when the cover closes the receptacle, member 34 is snugly received within the space 36 defined by the cover.

However, when cover 20 is moved to open position and the wares contained in receptacle 14 are thus disclosed to view, member 34 may be seated within slots 32; then it will extend upwardly from the notches so that its top edge will project within space 36 and up to a position closely adjacent and even in contact with the front wall 38 of the cover or into the corner formed by wall 38 and top wall 40. The length of slots 32, their distance from edge 18, their distance above the top edge of receptacle 12, and the depth of shallow space or recess 36 in cover 20 all cooperate to assure retention of member 34 with its top edge within the shallow recess when such an assembly has been completed, and preferably flexed in its association. In such relation, member 34 acts as a stop, resisting forward closing movement of cover 20, and thereby assuring that the cover will remain open under all normal circumstances.

Receptacle 14 preferably is divided up into a plurality of compartments 42 by means of partitions 44; these partitions, as seen in Fig. 2, extend vertically within the receptacle. However, since it is desired that member 34 may be positioned, in the described relationship, engaged 30 within the notches and extending up into the shallow recess of the cover, the partitions are made of such height that they will terminate below the top edge of receptacle 14, to arrange for a sufficient clearance so that member 34 may rest 35 in slots 32 or both in the slots and on top of the partitions. Of course, if desired, only the rear-most portions of partitions 44 need be fore-shortened in this manner.

Member 34 may serve as a separate closure for 40 receptacle 14; for this purpose, corners 48 of member 34 are snipped off. Then the defined edges 50 and 52 may be bent in such manner that the member may be received within receptacle 14 and be seated upon the top edges of the partitions, 45 as appears in Fig. 3. A pull-hole 54 is formed in the member to facilitate its use in such an association.

Therefore, not only is it possible, by a construction of this character, easily and simply to assemble a display container, compartmented for the reception of a plurality of articles displayed in separated relationship, and to display those articles in association with any suitable advertising matter upon member 34, but also there is assured 50 the retention of cover 20 in open position by means of the member carrying that advertising matter. Furthermore, the container may be broken up into two individual receptacles, each of which has its own cover and each of which can then function 55 independently for independent purposes.

Many other changes could be effected in the particular container structure designed, and in the methods for its construction set forth, and in specific details thereof, without substantially departing from the invention intended to be defined in the claims, the specific description herein being merely to illustrate an operative embodiment carrying out the spirit of the invention.

What is claimed as new and useful is:

1. In container structure for retaining articles and for displaying such articles, the container consisting of a casing for receiving the articles to be housed in the container, a plurality of partitions within the casing dividing it into a plu- 70 75

5. In container structure for retaining articles and for displaying such articles, the container consisting of a casing for receiving the articles to be housed in the container, a plurality of partitions within the casing dividing it into a plurality of compartments, the partitions being disposed substantially vertically and terminating short of the top edges of the casing, and a cover for retention in association with the casing, means for sustaining the cover, when opened away from the casing, in a fixed relation to the open top of the casing, and a card for association with the casing adapted to fit within the casing to lie flat on the upper edges of the partitions and cover the compartments formed thereby, the casing having means for engaging the lower edge of the card, with the upper edge thereof being engaged with the cover to lock the cover against unwarranted closing movement thereof.
10. 2. In container structure for retaining articles and for displaying such articles, the container consisting of a casing for receiving the articles to be housed in the container, a plurality of partitions within the casing dividing it into a plurality of compartments, the partitions being disposed substantially vertically and at least some of them terminating short of the top edges of the casing, and a cover for retention in association with the casing, means for sustaining the cover, when opened away from the casing, in a fixed relation to the open top of the casing, and a card for association with the casing, the casing having a notch for receiving an edge of the card, the card, when so received, resting on the top edges of the short partitions and the upper edge thereof being engaged with the cover to lock the cover against unwarranted closing movement thereof.
15. 3. In container structure for retaining articles and for displaying such articles, the container consisting of a casing for receiving the articles to be housed in the container, the top edges of the casing walls being formed with an upstanding bead, and a cover for retention in association with the casing, the cover seating over the bead and against the casing, means for sustaining the cover, when opened away from the casing, in a fixed relation to the open top of the casing, and a card for association with the casing, the card being of such extent that, when the cover is positioned in closed relationship, the card will extend substantially completely over the beaded portion of the casing wall edge, the casing bead having means for receiving the card, the card, when so received, being engaged with the cover to lock the cover against unwarranted closing movement thereof.
20. 4. In container structure for retaining articles and for displaying such articles, the container consisting of a casing for receiving the articles to be housed in the container, the top edges of the casing walls being formed with an upstanding bead, and a cover for retention in association with the casing, the cover seating over the bead and against the casing, means for sustaining the cover, when opened away from the casing, in a fixed relation to the open top of the casing, and a card for association with the casing, the card being of such extent that, when the cover is positioned in closed relationship, the card will extend substantially completely over the beaded portion of the casing wall edge, the casing bead having means for receiving the card, the card, when so received, being engaged with the cover to lock the cover against unwarranted closing movement thereof.
25. 5. In container structure for retaining articles and for displaying such articles, the container consisting of a casing for receiving the articles to be housed in the container, the top edges of the casing walls being formed with an upstanding bead, and a cover for retention in association with the casing, the cover seating over the bead and against the casing, means for sustaining the cover, when opened away from the casing, in a fixed relation to the open top of the casing, and a card for association with the casing and having thereon inscribed matter for advertising the articles in the containers, the card being of such extent that, when the cover is positioned in closed relationship, the card will extend substantially completely over the beaded portion of the casing wall edge, the casing bead having a plurality of notches for receiving the card, the card, when so received, resting on the top edges of the short partitions and being of sufficient length, and its position of engagement with the beaded edge being such, that it will engage with the cover to lock the cover against unwarranted closing movement thereof.
30. 6. In container structure for retaining articles and for displaying such articles, the container consisting of a casing for receiving the articles to be housed in the container, the top edges of the casing walls being formed with an upstanding bead, a plurality of partitions within the casing dividing it into a plurality of compartments, the partitions being disposed substantially vertically and terminating short of the top edges of the casing, and a cover for retention in association with the casing, the cover seating over the bead and against the casing, means for sustaining the cover, when opened away from the casing, in a fixed relation to the open top of the casing, and a card for association with the casing and having thereon inscribed matter for advertising the articles in the containers, the card being of such extent that, when the cover is positioned in closed relationship, the card will extend substantially completely over the beaded portion of the casing wall edge, the casing bead having a plurality of notches for receiving the card, the card, when so received, resting on the top edges of the short partitions and being of sufficient length, and its position of engagement with the beaded edge being such, that it will engage with the cover to lock the cover against unwarranted closing movement thereof.
35. 7. In container structure for retaining articles and for displaying such articles, the container consisting of a pair of nested receptacles, the inner receptacle providing means for receiving the articles to be housed in the container, and a cover for retention in association with the container, means for sustaining the cover, when opened away from the receptacles, in a fixed relation to the open top of the inner receptacle, and a card for association with the container, the inner receptacle having means for receiving the lower edge of said card, the card, when so received, having the upper edge thereof engaged with the cover to lock the cover against unwarranted closing movement thereof.
40. 8. In container structure for retaining articles and for displaying such articles, the container consisting of a pair of nested receptacles, the inner receptacle providing means for receiving the articles to be housed in the container, the inner receptacle being of greater height than the outer receptacle to provide a peripheral shoulder and an upwardly extending bead, and a cover for retention in association with the container, the cover, in closed position, seating over the bead and against the shoulder, means for sustaining the cover, when opened away from the receptacles, in a fixed relation to the open top of the inner receptacles, and a card for as-

5 association with the container, the inner receptacle bead having means for receiving the card, the card, when so received, being engaged with the cover to lock the cover against unwarranted closing movement thereof.

9. In container structure for retaining articles and for displaying such articles, the container consisting of a pair of nested receptacles, the inner receptacle providing means for receiving 10 the articles to be housed in the container, the inner receptacle being of greater height than the outer receptacle to provide a peripheral shoulder and an upwardly extending bead, a plurality of partitions within the inner receptacle dividing it 15 into a plurality of compartments, the partitions being disposed substantially vertically and at least some of them terminating short of the top edges of the receptacle, and a cover for retention in association with the container, the cover, in 20 closed position, seating over the bead and against the shoulder, means for sustaining the cover, when opened away from the receptacles, in a fixed relation to the open top of the inner receptacle, and a card for association with the container, the inner receptacle bead having means for receiving the card, the card, when so received, resting on the top edges of the short partitions and being engaged with the cover to lock the cover against unwarranted closing movement thereof.

10. In container structure for retaining articles and for displaying such articles, the container consisting of a pair of nested receptacles, the inner receptacle providing means for receiving 35 the articles to be housed in the container, the inner receptacle being of greater height than the outer receptacle to provide a peripheral shoulder and an upwardly extending bead, a plurality of partitions within the inner receptacle dividing it 40 into a plurality of compartments, the partitions being disposed substantially vertically and at least some of them terminating short of the top edges of the receptacle, and a cover for retention in association with the outer receptacle, the cover, in closed position, seating over the bead and against the shoulder, means for sustaining the cover, when 45 opened away from the receptacles, in a fixed relation to the open top of the inner receptacle, and a card for association with the container, the card being of such extent that, when the cover is positioned in closed relationship, the card will extend substantially completely over the top faces of the walls of the inner receptacle, the inner receptacle bead having a plurality of notches for receiving the card, the card, when so received, resting on 50 the top edges of the short partitions and being of sufficient length, and its position of engagement with the bead being such, that it will engage with the cover to lock the cover against unwarranted closing movement thereof.

11. In container structure for retaining articles 60 and for displaying such articles, the container consisting of a pair of nested receptacles, the inner receptacle providing means for receiving the articles to be housed in the container, the inner receptacle being of greater height than the outer receptacle to provide a peripheral shoulder and an upwardly extending bead, a plurality of partitions within the inner receptacle dividing it 65 into a plurality of compartments, the partitions

being disposed substantially vertically and at least some of them terminating short of the top edges of the receptacle, and a cover for retention in association with the container, the cover, in closed position, seating over the bead and against the shoulder, means for sustaining the cover, when 5 opened away from the receptacles, in a fixed relation to the open top of the inner receptacle, and a card for association with the container, the card being of such extent that, when the cover is 10 positioned in closed relationship, the card will extend substantially completely over the top faces of the walls of the inner receptacle, the inner receptacle bead having means for receiving the card, the card, when so received, resting on the top edges of the short partitions and being of sufficient length, and its position of engagement with the bead being such, that it will engage with the cover to lock the cover against unwarranted closing movement thereof.

12. In container structure for retaining articles and for displaying such articles, the container consisting of a pair of nested receptacles, the inner receptacle providing means for receiving the articles to be housed in the container, the inner 25 receptacle being of greater height than the outer receptacle to provide a peripheral shoulder and an upwardly extending bead, a plurality of partitions within the inner receptacle dividing it into a plurality of compartments, the partitions being 30 disposed substantially vertically and at least some of them terminating short of the top edges of the receptacle, and a cover for retention in association with the outer receptacle, the cover, in closed position, seating over the bead and against the 35 shoulder, means for sustaining the cover, when opened away from the receptacles, in a fixed relation to the open top of the inner receptacle, and a card for association with the container, the card being of such extent that, when the cover is positioned in closed relationship, the card will extend substantially completely over the top faces of the walls of the inner receptacle, the inner receptacle bead having a plurality of notches for receiving the card, the card, when so received, resting on 40 the top edges of the short partitions and being of sufficient length, and its position of engagement with the bead being such, that it will engage with the cover to lock the cover against unwarranted closing movement thereof.

13. A display device comprising a casing, a plurality of partitions within the casing dividing the same into a plurality of compartments, the partitions being disposed substantially vertically and terminating short of the top edges of the casing, a cover hinged to said casing for covering the same, a flat member substantially co-extensive with and adapted to fit within the upper end of the casing to lie flat on the upper edges of the partitions, flexible means for sustaining the cover when 55 opened away from the casing in a fixed relation to the open top of the casing, and said flat member being adapted to engage the casing at one end and the opened cover at the opposite end to lock the cover against unwarranted closing movement 60 thereof.

MAX SIMON.
